UNITED STATES PATENT OFFICE

2,468,019

INTERNAL-COMBUSTION DEVICE

Francis N. Bard, Highland Park, Ill.

Application March 28, 1946, Serial No. 657,649

8 Claims. (Cl. 123—149)

1

This invention relates to an internal combustion device, and more particularly to an internal combustion percussive device of the free piston type and to ignition means therefor including a magneto.

Internal combustion hammers of the free piston type have no crank shaft and, because of this, and because of the terrific vibration present in such a hammer, it has heretofore been considered impossible to use a magneto for generating the ignition spark. I have devised, and am here disclosing, magneto and ignition arrangements which are capable of operation by means other than a rotating crank shaft, which are properly timed and related to piston movement despite the absence of a crank shaft, and which are sufficiently rugged in construction to withstand the vibration present in a hammer of the free piston type.

This application is one of two copending companion applications relating to magneto ignition of an internal combustion hammer, my other companion application being Serial No. 657,650, filed March 28, 1946.

Various features and advantages of this invention will be apparent from the following specification and the drawings, in which:

Figure 1 is a side elevational view, partly in vertical section, of a free piston internal combustion hammer incorporating one embodiment of my inventions; Figure 2 is an enlarged vertical sectional view of the magneto and actuating assembly, along the line 2—2 of Figure 3; Figure 3 is an end view of the magneto with the cover removed, looking from the left of Figure 2; Figure 4 is a horizontal sectional view along the line 4—4 of Figure 3; Figure 5 is a schematic view showing the ignition circuit; Figure 6 is a partial view of an internal combustion hammer incorporating another embodiment of my inventions; Figure 7 is a vertical sectional view along the line 7—7 of Figure 6, and Figure 8 is a transverse sectional view through the magneto, along the line 8—8 of Figure 6.

The internal combustion percussive device with which I am here concerned is of a type providing a self-contained gasoline powered device for such purposes as pavement breaking, rock drilling, tamping, and the like. The cylinder 10 comprises the main body portion of the device and has a piston-hammer 11 freely reciprocable therein, being driven downwardly by the explosion of a combustible charge thereabove and being returned by the action of a return spring assisted by rebound. Hammers of

this general type, but with battery ignition, have been made and sold for some years by my company, and the description of the general principles of such hammers and of their operation will be kept brief since reference may be made to issued patents to supplement the present disclosure if desired, as for example Mould Patents 1,868,754 and 1,997,072 and Charles Patents 2,180,034 and 2,275,285, these being merely representative examples of the many issued patents on such hammers.

Briefly to describe the operation of the hammers here disclosed in Figures 1—5, gasoline in a tank 12 is mixed with air in carburetor 13 and delivered to the chamber 14 beneath the piston, where it is partly compressed by the downward stroke thereof. Near the bottom of the working stroke of the piston the charge is transferred from this lower space to the combustion space above the piston, at the top of the cylinder 10, through transfer passages which preferably include passageway portions in the piston 11 and the portion 15 in the cylinder 10. The combustible charge thus provided in the upper end of the cylinder is then further compressed on the upward stroke of the piston, effected primarily by the return spring 16, and at a proper time with respect to piston movement this charge is ignited by causing a spark to jump across the electrodes of the spark plug 17. Combustion of this charge drives the piston downward on its working stroke, the lower end of the piston eventually striking the top of the anvil 18 in the anvil housing 19 and the blow thus being transmitted to the tool 20. As the piston nears the lower end of its travel the burned gases are discharged through the exhaust port 21, a fresh charge transferred to the space above the piston, and the cycle of operation repeated.

Handles 22 and 23 are provided to enable a workman to spot the tool in a desired working point, to maintain the hammer in operative position during working thereof, and to lift the hammer between operations. Starting is accomplished by manually depressing the starting rod 24, normally biased to the position shown by the spring 25, until the piston 11 is near the lower end of its travel, then releasing it, then again pushing down on the starting rod and releasing it, an explosion taking place as soon as a charge has been drawn into the sub-piston compression space and transferred to the combustion space above the piston. The means for providing ignition of the combustible charge in properly timed relation to piston movement and

in a manner obviating the necessity for cables, storage batteries, and the like, comprises the improvement to which this and my companion application are directed, and these will now be more particularly described.

Referring now more particularly to Figures 2, 3 and 4, a magneto identified in general as A will be seen to be mounted on the side wall of the cylinder 10, this magneto comprising as its principal parts an outer permanent magnet or pole assembly 26, a laterally movable armature member 27, and a coil 28 wound thereon, this coil comprising a primary and secondary in accordance with the practice followed in rotary magnetos of a more conventional type.

The movable armature and coil of the magneto are rigidly mounted on a rod-like member 29 mounted for longitudinal or axial movement, one end of this rod member 29 being mounted in the side wall of the cylinder 10 for movement in a direction transverse to that of the piston 11 and being provided with a roller 30 in engagement with the side wall of the piston at all times during its movement, the piston being shown at the uppermost limit of its movement in Figures 1 and 2. The piston is provided on its side wall with a cam groove 11a having a shouldered portion 11a' so that the roller 30 and rod member 29 are moved outwardly of the cylinder (i. e., to the left as viewed in Figure 2) at the properly timed instant when a spark is to be generated at the spark plug, analogous to the breaker point actuating arrangement shown in Mould Patent 1,868,754 mentioned heretofore.

The other or outer end of the rod member 29 is mounted in suitable bearings in the block 31, being constantly biased inwardly (to the right as viewed in Figure 2) by the spring 32. The outer end of the rod member 29 carries an adjustable stud 29a bearing against a spring metal member 33 fixedly mounted at one end (the right hand end as viewed in Figure 3) and carrying a movable breaker point 34a adapted to cooperate with a fixedly (though adjustably) mounted breaker point 34b. The whole assembly is enclosed by a cover 35 having a high tension cable 36 leading therefrom to the central or "hot" electrode of the spark plug.

When the piston is in the central and lower portions of its range of movement, the roller 30 would lie in the groove 11a in the piston wall and the armature member 27 would be to the right of the position shown in Figure 2, in good magnetic relationship to the pole segments 26a and 26b and spaced from the pole segments 26c and 26d. The outer pole structure would include permanent magnetic material, as Alnico, and the arrangement might be such that the pole segment 26a is north and the pole segment 26b south while the pole segment 26c is south and the pole segment 26d north. With the armature at the innermost limit of its movement toward the cylinder wall, the upper end would have a north magnetic polarity and its lower end would have a south magnetic polarity, whereas if the armature is shifted to the position shown in Figure 2 by movement of the roller 30 up the cam shoulder 11a' on the piston, the upper end of the armature would be south and the lower end north, thus resulting in a complete reversal of magnetic flux conditions through the winding 28. At an appropriately timed instant when the current in the primary 28a of the winding (referring now more particularly to Figure 5) is at or near its maximum, the movement of the rod member 29

would bring the stud 29a into engagement with the spring member 33 and cause separation of the breaker points 34, resulting in a complete collapse of the magnetic field around the primary 5 and the generation of a very high voltage (of the order of 10,000 volts) impulse in the secondary 28b which would be delivered to the spark plug 67 through the cable 36 and cause sparking at the plug electrodes, with attendant ignition of the combustible charge in the cylinder. In order to minimize arcing at the breaker points, a condenser 36 is utilized in conventional manner in shunt with such points; and the return connections of the circuit are made through a ground, 10 in this case the frame or main body structure of the hammer. The entire assembly for the first 15 time provides a satisfactory and usable ignition system for an internal combustion hammer of the free piston type, satisfactorily operable without a crank shaft and capable of withstanding the tremendous vibration present in such a hammer, obviating the necessity for storage batteries and cables to provide ignition as has heretofore been customarily the case.

Another embodiment of my inventions for magneto ignition of an internal combustion hammer of the free piston type is illustrated in Figures 6, 7 and 8. In order to keep the description of this modification as brief as possible, reference numerals 50 higher than those heretofore used will be applied to parts analogous to those described in connection with Figures 1-5, so that reference back to the earlier portions of the specification may be made if desired.

The hammer again comprises as its principal body portion a cylinder 60 having a piston 61 freely reciprocable therein, a combustible charge being ignited above this piston at an appropriate time by ignition means such as a spark plug 67 35 to drive the piston downward, return being by a return spring and rebound. In this case the magneto, indicated in general as B, is of the type 40 with a rotatable or oscillatable rotor or armature 71 carrying primary and secondary windings 78a and 78b and disposed in operative relation to an outer pole structure 76. The pole relationships are again such that movement of the armature 71 (in this case oscillation back and forth through a rather limited range of the order of 15°) is sufficient to create the desired primary current 45 which is broken at an appropriate instant by suitable breaker points to provide the high tension output from the secondary 78b.

In this case the actuating means for the movable parts of the magneto again comprises a member movably mounted in the side wall of the cylinder 60, as the member 79, but in this case the member is rotatably mounted therein. The inner end of the member 79 is provided with an extending crank arm portion 79b carrying the roller 80, the roller in this case bearing against the side wall of a slot cut in the side of the piston 11, as the side wall 71a of such slot. The rod member 79 is normally rotatably biased by the spring 88 in a direction tending to keep the roller 80 always in engagement with the groove wall during movement of the piston; and at the appropriate time with relation to piston movement, the roller 80 moves down into the depressed portion 71a' to effect a sudden fairly rapid partial rotation of the armature or rotor member 71 resulting in generation of a spark at the electrodes of the spark plug 67. If the spark thus produced fails to fire the combustible charge for any reason further upward movement of the pis-

ton causes the roller to drop into the second depressed portion $71a''$, resulting in a second spark, the plurality of sparking operations improving the certainty of ignition. The concept of using the side of a groove cut into the wall of a piston is more fully disclosed and claimed in the co-pending Breitenstein and Ingebretsen application Serial No. 593,386, filed May 12, 1945, now Patent No. 2,442,284, although there was heretofore no concept of such an arrangement operating anything more than the breaker point.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. An internal combustion device of the free-piston type, including: a cylinder adapted to have a combustible charge therein; a piston freely reciprocable therein; electrical ignition means in one end of the cylinder; a magneto for generating a spark at said ignition means; and actuating means including means in engagement with said piston at all times during its reciprocation for actuating the magneto by and in accordance with movement of said piston for effecting generation of the spark when the piston approaches said end of the cylinder.

2. An internal combustion percussive device of the free-piston type, including: a cylinder adapted to have a combustible charge therein; a piston freely reciprocable therein; a tool adapted to have impacts transmitted thereto upon reciprocation of said piston; electrical ignition means in one end of the cylinder; a magneto for generating a spark at said ignition means; and an actuating arrangement including a follower member in engagement with said piston at all times during its reciprocation for actuating the magneto by and in accordance with movement of said piston for effecting generation of the spark when the piston approaches said end of the cylinder.

3. An internal combustion device of the free-piston type, including: a cylinder adapted to have a combustible charge therein; a piston freely reciprocable therein; electrical ignition means in one end of the cylinder; a magneto for generating a spark at said ignition means; and actuating means for the magneto including a member movably mounted in a side wall of said cylinder and having means at one end in engagement with said piston at all times during its reciprocation for actuating the magneto by and in accordance with movement of said piston, the construction and arrangement being such that a plurality of sparks are generated when the piston approaches said end of the cylinder.

4. An internal combustion percussive device of the free-piston type, including: a cylinder adapted to have a combustible charge therein; a piston freely reciprocable therein; a tool adapted to have impacts transmitted thereto upon reciprocation of said piston; electrical ignition means in one end of the cylinder; a magneto for generating a spark at said ignition means; and actuating means for the magneto including a member movably mounted in a side wall of said cylinder and having a roller means at one end in engagement with said piston at all times during its reciprocation for actuating the magneto by and in accordance with movement of said piston for effecting

generation of the spark when the piston approaches said end of the cylinder.

5. An internal combustion percussive device of the free-piston type, including: a cylinder adapted to have a combustible charge therein; a piston freely reciprocable therein; a tool adapted to have impacts transmitted thereto upon reciprocation of said piston; electrical ignition means in one end of the cylinder; a magneto for generating a spark at said ignition means, this magneto having a laterally movable armature; and actuating means for the magneto including a plunger longitudinally movable in a side wall of said cylinder and having a roller means at one end in engagement with said piston at all times during its reciprocation for actuating the magneto by and in accordance with movement of said piston for effecting generation of the spark when the piston approaches said end of the cylinder.

20 6. An internal combustion percussive device of the free-piston type, including: a cylinder adapted to have a combustible charge therein; a piston freely reciprocable therein; a tool adapted to have impacts transmitted thereto upon reciprocation of said piston; electrical ignition means in one end of the cylinder; a magneto for generating a spark at said ignition means, this magneto having an oscillatable armature and at least one movable breaker point; and an actuating arrangement for oscillating the armature and moving the breaker point including a member rotatably movable in a side wall of said cylinder and having a roller at one end in engagement with said piston at all times during its reciprocation for actuating the magneto by and in accordance with movement of said piston, the portion of the piston engaged by the roller having a plurality of similar variations near one end such that a plurality of sparks are generated when the piston approaches said end of the cylinder.

35 7. An internal combustion percussive device of the free-piston type, including: a cylinder adapted to have a combustible charge therein; a piston freely reciprocable therein; a tool adapted to have impacts transmitted thereto upon reciprocation of said piston; electrical ignition means in one end of the cylinder; a magneto for generating a spark at said ignition means, this magneto having a rotatably movable armature and at least one movable breaker point; and actuating means for moving the armature and breaker point including a member rotatably mounted in a side wall of said cylinder and having a roller means at one end in engagement with said piston at all times during its reciprocation for actuating the magneto by and in accordance with movement of said piston for effecting generation of the spark when the piston approaches said end of the cylinder.

45 8. An internal combustion percussive device of the free-piston type, including: a cylinder adapted to have a combustible charge therein; a piston freely reciprocable therein; a tool adapted to have impacts transmitted thereto upon reciprocation of said piston; electrical ignition means in one end of the cylinder; a magneto for generating a spark at said ignition means, this magneto having a rotatably movable armature and at least one movable breaker point; and an actuating arrangement for moving the armature and breaker point including a member rotatably mounted in a side wall of said cylinder and having a roller at one end in engagement with said piston at all times during its reciprocation for actuating the magneto by and in accordance with movement of said piston, the portion of the piston engaged by

the roller having a plurality of similar variations near one end such that a plurality of sparks are generated when the piston approaches said end of the cylinder.
